UNITED STATES PATENT OFFICE.

ELISHA DAVID PEPPER, OF PICKENS, MISSISSIPPI.

AUTOMATIC RELEASE.

1,375,605.

Specification of Letters Patent. Patented Apr. 19, 1921.

Application filed June 5, 1920. Serial No. 386,805.

To all whom it may concern:

Be it known that I, ELISHA D. PEPPER, a citizen of the United States, and a resident of Pickens, in the county of Holmes and State of Mississippi, have invented a new and Improved Automatic Release, of which the following is a full, clear, and exact description.

This invention relates to improvements in automatic releases, an object of the invention being to provide a device of this character which is especially adapted for use with plows, and so constructed that when the plow strikes an immovable obstruction in the ground the draft means will be automatically unhitched from the plow.

A further object is to provide a device of this type which may be used either with horse drawn or tractor drawn plows, which is practical and durable in use and which will most efficiently perform the functions for which it is intended.

With these and other objects in view the invention consists in certain novel features of construction and combination and arrangement of parts as will be more fully hereinafter described and pointed out in the claims.

In the accompanying drawings—
30 Figure 1 is a top plan view of my improved device.

Fig. 2 is a view in side elevation.

Fig. 3 is a view in transverse section on the line 3—3 of Fig. 2; and

35 Fig. 4 is a fragmentary view on a smaller scale showing the tongue or draft means disconnected from the drawbar.

1 represents a plow beam having a longitudinal recess 2 in its forward end. A U-shaped bracket 3 fits over the recessed end of the beam 1 and has its side members 4 bolted to the sides of the shaft as illustrated at 5. The bracket 3 is provided with an opening 6 at its intermediate portion and 45 also with an integral enlargement or boss 7 around the opening 6 adapted to guide the drawbar 8 which is projected through the opening 6 in the bracket 3 and extends into the recess 2 in the plow beam 1.

50 The inner end of the drawbar 8 which is located within the recess 2 is provided with a transversely positioned plate or disk 9 which is secured to the drawbar by means of a screw 10.

55 A spiral spring 11 is provided around the

drawbar 8 between the plate 10 and the bracket 3.

The other end of the drawbar 8 is bifurcated as shown at 12 and an angular coupling member 13 is pivoted in the bifurcated portion on a bolt 14. The shape of the member 13 is clearly illustrated in Figs. 2 and 4.

A stirrup 15 depends from the drawbar 8 and is pivotally connected to the drawbar at its extremities by means of a bolt 8^a. The member 12 is formed with a reduced lug 16 upon its free end adapted to be engaged and supported by the intermediate or lower portion of the stirrup 15.

A tongue or connecting member 17 for 70 the draft animals or other draft means is provided with a clevis 18 which couples with the member 13. A chain or other flexible connecting device 19 loosely connects the stirrup 15 with a hook 20 on the bracket 3. 75

A spring 21 is connected at one end to the cross piece 15^a in the stirrup 15 and has its other end secured to an eye 15^b on a depending enlargement 22 on the under face of the drawbar 8 and holds the stirrup in 80 position on the lug 16 and against a shoulder 16^a formed at the free end of member 13 and limiting the forward pivotal movement of the stirrup. The enlargement 12 also forms an abutment or shoulder limiting the 85 rearward movement of the clevis 18.

In operation when the plow strikes an immovable obstruction such as a rock or stump the plow will be stopped. The continued pull on the drawbar 8 will pull the 90 drawbar forwardly in the recess 2, compressing the spring 11 abnormally. It can be readily seen that an extreme forward movement of the drawbar 8 with relation to the plow beam 1 will increase the distance 95 between the hook 20 and the stirrup 15 so that the chain will become taut and pull the stirrup 15 rearwardly, releasing the coupling member 13 and permitting the clevis to draw the latter to the position 100 shown in Fig. 4, and hence the clevis will slip over the member 13 thus unhitching the plow from its draft means. The spring 11 will then operate to return the drawbar to its normal position. 105

It is of course to be understood that under a normal strain the spring 11 exerts sufficient pressure upon the drawbar 8 to prevent any forward movement of the drawbar sufficient to cause an operative action of the 110

chain 19 and a consequent release of the member 13, and that only a sudden jar or jolt caused by the plow striking a relatively immovable object will be sufficient to 5 unhitch the draft animals or tractor, as the case may be, from the plow.

It is also to be understood that the hook 20 may engage any one of the links of the chain 19 so that the device may be made adjustable to uncouple under strains of greater or less degree depending upon the ground 10 to be plowed and the kind of obstructions likely to be encountered.

Various slight changes and alterations 15 might be made in the general form of the parts described without departing from the spirit of my invention, and hence I do not limit myself to the precise details set forth, but consider myself at liberty to make such 20 slight changes and alterations as fairly fall within the spirit and scope of the appended claims.

I claim:

1. A device of the character stated, comprising a beam, a drawbar movably connected to the beam and projecting forwardly therefrom, a spring engaging the drawbar and offering elastic resistance to the independent forward movement thereof, a rearwardly projecting coupling member pivotally connected at its forward end to the drawbar, a stirrup pivotally connected to the drawbar and normally engaging the free rear end of the coupling member holding the same in operative position, and a normally slack flexible connecting device connecting the stirrup and beam and adapted upon continued forward movement of the drawbar after the connecting device is taut, 40 to cause a release of the stirrup from the coupling member.

2. A device of the character stated, comprising a beam, a drawbar movably connected to the beam and projecting forwardly therefrom, a spring engaging the drawbar and offering elastic resistance to the independent forward movement thereof, a rearwardly projecting coupling member pivotally connected at its forward end to the drawbar, a stirrup pivotally connected to the drawbar and normally engaging the free rear end of the coupling member holding the same in operative position, a normally slack flexible connecting device con-

necting the stirrup and beam and adapted upon continued forward movement of the drawbar after the connecting device is taut, to cause a release of the stirrup from the coupling member, said flexible connecting device comprising a chain connected at one end to the stirrup, and a hook on the beam for selectively engaging one of the links of the chain, whereby the chain may be given the desired slack.

3. A device of the character described, comprising a beam, a drawbar movably connected to the beam and projecting forwardly therefrom, a spring engaging the drawbar and offering elastic resistance to the independent forward movement thereof, a coupling member pivotally connected to the drawbar and normally projecting rearwardly and in substantial parallelism therewith, a lug on the rear end of the coupling member, a stirrup pivotally connected to the drawbar and normally engaging the lug, a spring connecting the stirrup with the drawbar and exerting spring pressure on the stirrup holding the same against the end of the coupling member, and a normally slack flexible connecting device connecting the stirrup and beam and adapted upon continued forward movement of the drawbar after the connecting device is taut, to cause a release of the stirrup from the coupling member.

4. A device of the character described, comprising a beam, a drawbar movably connected to the beam and projecting forwardly therefrom, a spring engaging the drawbar and offering elastic resistance to the independent forward movement thereof, an angular coupling member pivotally connected to the drawbar and normally projecting rearwardly and in substantial parallelism therewith, said coupling member adapted to receive a link, a projection on the drawbar in rear of the pivotal connection of the coupling member forming a shoulder, whereby the link is limited in its longitudinal movement relative to the drawbar by reason of said shoulder and the forward portion of the coupling member, a stirrup on the drawbar holding the coupling member in normal position, and a normally slack flexible connecting device connecting the stirrup with the beam.

ELISHA DAVID PEPPER.
